BOWLING BALL BAG

Frederick M. Westley, Kirtland, Ohio

Application May 25, 1951, Serial No. 228,214

4 Claims. (Cl. 219—46)

1

This invention relates in general to bowling ball bags.

It has been my observation that as long as the temperature of the ball remains as high as the ordinary room temperature of the bowling alley hall, the ball after having been wiped by a dry cloth, will remain dry and easily handled for bowling purposes. When, however, the ball is appreciably colder than the temperature of the bowling alley hall, condensation occurs, leaving the surface of the ball moist and slippery. This is due to the material composition of the ball. This is such a pronounced and enduring condition that repeated wipings with a cloth fails to eliminate it. The only remedy in such a case is to raise the temperature of the ball to one that approximates that of the hall. Of course, this could be done by placing the ball in an oven or by the patrons leaving their balls on the rack or in lockers in a bowling alley hall, the managers of which keep their hall well heated at all times.

However, it is especially true that devotees of the bowling game, commonly known as ten-pins, employing bowling balls with thumb and finger holes due to the large size of the ball, generally prefer to own and use their own private ball. This is because they are measured for their own particular grip, or spacing of their thumb and finger holes, with respect to the size of the ball. At many halls the locker space is inadequate or too expensive for the bowler. Many times the bowler is not content to bowl in one hall alone but likes to visit other halls. He may also belong to more than one league or compete in bowling tournaments. In cold weather the ball becomes cold during the bowler's trip to the hall. In many cases the bowler drives to his place of employment with his ball in a bag in his automobile. After his day's or night's work he proceeds to the bowling alley hall for a usual three-game league competition. The ball is cold, due to the prevailing outside cold weather. The bowler repeatedly wipes the ball with a dry cloth but it remains moist and slippery due to atmospheric condensation. The ball is difficult to handle and the bowler's score suffers materially. The hall has no facilities to heat the balls of the bowlers. In the case of cold outside weather, the chances are that the temperature of the ball approaches that of the hall at the time of the conclusion of the three-game competition. Thus, the ball is dry after the night's bowling engagement has been concluded.

It is, therefore, one of the primary objects of my invention to remedy this prevailing situation

2

by providing a simple, inexpensive, efficient and expedient means, as an accessory device to the bowling ball bag, whereby the ball may be maintained at a predetermined temperature, at least equal to ordinary room temperature, especially at times when the exterior of the bag is being exposed to cold temperatures below that of ordinary room temperature.

Another object is to provide such a heating element in the form of a fabric pad with electrical resistance elements embedded therein regardless of the source of current, whether it be a dry battery, a power line or a suitable plug leading to an automotive vehicle dashboard and its battery or ignition system.

Another object is to provide such a heating pad that will not interfere with the conventional centering and shock absorbing cup and its intended functions in the bowling ball bag.

Another object is to provide such a heating pad that will provide means for specifically enclosing the ball within the bag in order to provide room for such other bowler's accessories as shoes, and the like, in either the remaining space, or other compartments, within the bowling ball bag, as a whole.

Another object is to provide, as a bowling ball bag accessory, means for a quick detachable source of electric current for the electric heating pad.

With the foregoing and other objects in view, the invention resides in the combination of parts and in the details of construction hereinafter set forth in the following specification and appended claims, certain embodiments thereof being illustrated in the accompanying drawings, in which:

Figure 1 is a view in general side elevation, partly in perspective, of a bowling ball bag constituting one form that my invention may take, the bag being shown partly broken away to show the bowling ball, centering cup and ball heating pad, and also a side bag compartment for the optional enclosure of a dry cell battery and a lead to a source of electricity for the electrical resistance wires of the bowling ball heating pad, the bag being of the general type that is more or less of dimensions that conform laterally with the outside dimensions of the ball;

Figure 2 is a view in cross section taken through the type of bag shown in Figure 1, showing the ball in the pad, and bowling shoes in assembled position in full lines;

Figure 3 is a view in end elevation of the bowl-

ing bag showing an electrical power source socket and rheostat control;

Figure 4 is a plan view of the bowling ball heating pad, shown in flattened position, the electrical heating resistance wires embedded in the pad being shown in dotted lines;

Figure 5 is a fragmentary detail view in section of the heating pad;

Figure 6 is a view in side elevation of a slightly different type of bowling ball bag which is elongated with respect to the type specifically shown in Figure 1, the bag being shown partially broken away to show the ball, centering cup and heating pad; and

Figure 7 is an enlarged detail view of the bowling ball centering and shock absorbing cup and a fragmentary portion of the bowling ball bag.

Referring more particularly to the drawings, I have shown in Figures 1, 2, and 3 a generally conventional bowling ball bag 1. It is furthermore conventional practice to employ a cup 2 on the base of the bag. The cup 2 is preferably of cushioning resilient material. Its cup formation assists in properly positioning the ball within the bag for ball carrying purposes and its cushioning characteristics assist in the protection of the ball in the bowler's handling of the ball enclosing bag. In Figures 1 and 2 the centering cup 2 may be secured by any suitable easily removable or relatively permanent securing means to the bottom base of the bag. Also in Figures 1 and 2 the bowling ball 3 is shown positioned in the centering cup in the bag.

Now, in further pursuance of the object of my invention, I have shown in detail in Figures 4 and 5, one form that my invention may take with respect to the bowling ball heating pad to be incorporated in the bag. This heating pad is generally indicated at 4 and may include a strip of fabrics with layers 5 and 6 with electrical resistance wires 7 suitably imbedded therein. One form that the heating pad may take is shown in plan view in Figure 4 which includes a central aperture 9 to embrace and not interfere with usual ball centering, positioning and shock absorbing functions of the resilient cup 2. As shown in Figures 1, 2, and 4, the electric heating pad 4 is preferably provided with a conventional slide fastener 8, commonly known as a zipper, for joining the two top ends of the pad to enclose the ball and leave a remaining space within the bag to enclose additional accessories within the bag, such as a pair of bowling shoes 18 as shown in Figure 2.

Given a suitable source of electrical current, the modification of my invention shown in Figure 6 does not materially differ in fundamental concept. The bag is of the elongated type in which the centering and positioning cup 2 with its removably connecting snap elements 16 and 17 on the cup and bag base are more important as such to provide greater remaining packing space within the bag.

The source of electrical power to make the resistance wires 7 effective as a heating element for the heating pad 4 may vary among a dry battery, a power line source or a plug connection with the dashboard of an automotive vehicle, and this applies to both types of bags.

Accordingly, in Figure 1 I have shown a separate pocket 12 to enclose a suitable dry cell battery. This pocket 12 is shown to be arranged externally of the bag but it may be arranged internally of the bag if desired. Element 13

merely illustrates a cover flap for pocket 12. The plug and wire assembly shown at 14 merely illustrates a removable connection between the resistance wires 7 and any source of electric current. Element 10 illustrates any type of rheostat for controlling the current supply and the attending heat supply from the pad to the ball.

From the foregoing it will be seen that I have provided a new and novel combination including a bowling ball bag having incorporated therein an electrical heating pad with electrical resistance wires with an adjustable current supply and which pad provides a separated compartment for other bowling accessories and does not interfere with the centering, positioning and shock absorbing functions of the conventional ball cup in the base of the bag.

In order to accommodate the resistance wires to provide an adequate heating pad, the pad is relatively thick. If no relief, such as the aperture 9, were provided, the pad due to its thickness, would interfere with the bowling ball positioning function of the cup. It is for this reason, as before stated, that I have provided the aperture 9.

I claim:

1. In a bowling ball bag, a bowling ball positioning cup of cushioning material carried by the base of said bag, the inner surface of said cup being inclined upwardly outwardly to provide a frustro-conical pocket to receive said ball and conform to a portion of its spherical surface, said bag having a heating pad comprising a fabric pad with imbedded electrical resistance wires for heating said ball, said pad having an aperture therein to surround and accommodate said cup, said pad being adapted in assembled position to substantially encircle said ball within said bag to separate said ball from the remainder of the interior of said bag to provide space for the accommodation of other bowling accessories, said pad having releasable closure means.

2. In a bowling ball bag, a bowling ball positioning cup of cushioning material carried by the base of said bag, the inner surface of said cup being inclined upwardly outwardly to provide a frustro-conical pocket to receive said ball and conform to a portion of its spherical surface, said bag having a heating pad comprising a fabric pad with imbedded electrical resistance wires for heating said ball, said pad having an aperture therein to surround and accommodate said cup, said pad being adapted in assembled position to substantially encircle said ball within said bag to separate said ball from the remainder of the interior of said bag to provide space for the accommodation of other bowling accessories, said pad having releasable closure means, a source of electrical current and a manually operable electrical current control.

3. In a bowling ball bag, a bowling ball positioning cup of cushioning material carried by the base of said bag, the inner surface of said cup being inclined upwardly outwardly to provide a frustro-conical pocket to receive said ball and conform to a portion of its spherical surface, said bag having a heating pad comprising a fabric pad with imbedded electrical resistance wires for heating said ball, said pad having an aperture therein to surround and accommodate said cup.

4. In a bowling ball bag, a bowling ball positioning cup of cushioning material carried by the base of said bag, the inner surface of said cup being inclined upwardly outwardly to provide a

frustro-conical pocket to receive said ball and conform to a portion of its spherical surface, said bag having a heating pad of fabric material with electrical resistance wires embedded in said pad and connectable to an electrical source said pad being adapted to be wrapped around said ball to electrically heat the ball, said pad including an area, devoid of said resistance wires, and adapted to be placed under said ball.

FREDERICK M. WESTLEY. 10
